CLAIM

The ornamental design for a luminaire, as shown and described.

DESCRIPTION

FIG. 1 is a top, front perspective view of a luminaire showing my new design;

FIG. 2 is a side elevational view thereof, the opposite side being a mirror image;

FIG. 3 is a front elevational view thereof;

FIG. 4 is a top plan view thereof;

FIG. 5 is a bottom view thereof;

FIG. 6 is a rear elevational view thereof;

FIG. 7 is a top plan view of a second embodiment of my new design, the second embodiment being identical to the first except for the omission of recesses in its top surface;

FIG. 8 is a top plan view of a third embodiment of my new design, the third embodiment being identical to the first except for the longitudinal rather than latitudinal recesses in its top surface;

FIG. 9 is a side elevational view of a fourth embodiment of my new design, the fourth embodiment being identical to the first embodiment except for the omission of recesses in its top surface and its flat bottom surface; and FIG. 10 is a side elevational view of a fifth embodiment of my new design, the fifth embodiment being identical to the first embodiment except for the longitudinal recesses in its top surface and its flat bottom surface.

FIG. 3.

FIG. 6.

FIG. 5.

FIG. 7.

FIG. 8.

FIG. 9.

FIG. 10.
